UNITED STATES PATENT OFFICE.

JOHANN FÜLSCHER, OF HAMBURG-EIMSBÜTTEL, GERMANY.

MOLDING-MACHINE.

1,106,645.

Specification of Letters Patent.

Patented Aug. 11, 1914.

Application filed July 17, 1913. Serial No. 779,519.

To all whom it may concern:

Be it known that I, JOHANN FÜLSCHER, engineer, a subject of the German Emperor, residing at 27 Stellingerweg, Hamburg-5 Eimsbüttel, Germany, have invented certain new and useful Improvements in Molding-Machines; and I do hereby declare the following to be a full, clear, and exact description of the invention, such as will enable 10 others skilled in the art to which it appertains to make and use the same.

This invention relates to molding machines and has for its object to provide a machine which will automatically produce 15 satisfactory molds in a single operation.

In existing molding machines in which the compression of the sand from which the mold is formed is effected by the movement of the pattern plate, when several adjoining 20 patterns having sharp edges or steep walls, are to be molded, they require, in addition to the mechanical compression, ramming by hand or by some mechanical device, so that the formation of the mold occupies a 25 great deal of time. In such machines either the pattern plate carries the sand which is pressed upward into a mold box having a flat bottom, or the pattern plate is pressed downward from above into the sand contained in the mold box. These machines do 30 not produce satisfactory molds, as either the sand does not penetrate in a uniform manner and sufficiently far into the deepest recesses of the molds or the sand in close 35 proximity to projections on the pattern is excessively compressed.

The present invention enables a uniform and closely compressed mold to be produced even in case of patterns having sharp corners or steep walls. According to this invention the pattern plate compresses the molding sand placed thereon upward into a mold box the bottom of which has projections corresponding to the patterns, these 45 projections during the molding, penetrating into the layers of sand occupying the deeper recesses between the projecting parts of the pattern.

One construction according to this invention is illustrated in the accompanying drawing in which—

Figure 1 is a vertical section of the machine, Fig. 2 shows how the sand is compressed when hand ramming is omitted in 55 existing molding machines, and Fig. 3 shows

how the compression is produced by the present machine.

In the lower part of the frame *a* of the machine is formed a cylinder *b* in which moves a piston *c*. The piston *c* has an upper part *d* formed into a chamber and held laterally by the supports *e* of the machine frame. Within the upper part *d* is arranged a second cylinder *g* in which moves a piston *h*, the upper end *k* of which constitutes a 60 table which can be reciprocated within the walls of the sand-retaining frame *m*. The table *k* carries the pattern plate *n* to which are secured the pattern members *p*, the mold box *f* being supported on the sand box 65 or sand-retaining frame *m*. Above the mold box *f* is arranged a counter-pressure plate *s* traveling on rollers *r*. The motive fluid is supplied to the cylinder *b* through a pipe *v* and to the cylinder *g* through a pipe *w*.

After the sand box or frame *m* is filled with sand, and the counter-pressure plate *s* has been brought into the position shown in Fig. 1, water under pressure is admitted into the cylinder *b*. The piston *c* raises the part 70 *d* and the box *m* together with the table *k* and presses the mold box *f* against the counter-pressure plate *s*. Water under pressure is then admitted into the cylinder *g* whereby the table *k* together with the pattern plate *n* 75 is raised independently of the piston *c* and the molding sand from the retaining frame *m* is forced into the molding box *f*. The projections *o* of the underside of the mold box *f* then penetrate into the sand and give 80 the latter the desired additional compression. Without this compression, the sand, as shown in Fig. 2, would be more strongly 85 compressed around the points or projections of the pattern than in the deeper portions *q*.

The shape of the projections *o* depends on the outline of the patterns, and must be made as shown in such manner that the mold eventually has the same density 90 throughout.

By the expression "pattern members" as employed in the description and claims, it is intended to cover either multiple patterns having steep sides and carried by the pattern plate, or, in the alternative, a pattern or patterns having steep sided projections with relatively deep recesses therebetween.

What I claim as my invention and desire to secure by Letters Patent is:—

1. In a molding machine, the combination 110

of a pattern plate, a sand-retaining frame surrounding the same, steep-sided pattern members secured to the plate having recesses therebetween, a mold box disposed above the frame, means for raising the plate and projections formed on the underside of the mold box adapted to enter and compress the sand in the recesses when the plate is raised.

2. In a molding machine, the combination 10 of a pattern plate, steep-sided pattern members secured thereon having recesses therebetween, a sand-retaining frame surrounding the plate, a mold box supported by said frame, means for raising the plate, and projections on the underside of the mold box corresponding in shape to the deeper recesses between the pattern members adapted to enter and compress the sand in the said deeper recesses when the plate is raised.

3. In a molding machine, the combination 20 of a pattern plate, steep-sided pattern members secured thereto, a sand-retaining frame surrounding the plate, a mold box arranged above the pattern, means for simultaneously raising the plate and sand-retaining frame, additional means for raising the plate alone and projections on the underside of the mold box, corresponding in shape with the recesses in and around the pattern members 25 adapted to enter and compress the sand in the said recesses when the pattern plate alone is raised.

4. In a molding machine, the combination of a pattern plate, a plurality of steep-sided

patterns secured thereto, a sand-retaining 35 frame surrounding the plate, a mold box arranged above the patterns, a counter-pressure member therefor, means for simultaneously raising the plate patterns and sand-retaining frame, additional means for 40 raising the plate and patterns relatively to said frame and projections on the underside of the mold box corresponding in shape and number to the deeper recesses between the patterns adapted to enter said recesses 45 and additionally compress the sand therein when the plate and patterns are raised relatively to the sand-retaining frame.

5. In a molding machine, the combination 50 of a pattern plate, pattern members carried thereby having relatively steep sides, a sand-retaining frame surrounding the plate, a mold box disposed in alignment with the said frame and having projections on its under side corresponding substantially in 55 shape and number with the depressions between the pattern members, and means for effecting relative movement of the pattern plate and mold box, whereby a uniform compression of the sand forming the mold is 60 effected.

In testimony whereof I have affixed my signature, in presence of two witnesses.

JOHANN FÜLSCHER.
